Patented Apr. 17, 1917.

CHRISTINA SWANSON Inventor

By Watson E. Coleman

Attorney

UNITED STATES PATENT OFFICE.

CHRISTINA SWANSON, OF PORTLAND, OREGON, ASSIGNOR TO JOHN KOPF, OF PORTLAND, OREGON.

HAT-FASTENER.

1,223,008.

Specification of Letters Patent. Patented Apr. 17, 1917.

Application filed October 8, 1916. Serial No. 123,557.

To all whom it may concern:

Be it known that I, CHRISTINA SWANSON, a citizen of the United States, residing at Portland, in the county of Multnomah and State of Oregon, have invented certain new and useful Improvements in Hat-Fasteners, of which the following is a specification, reference being had to the accompanying drawings.

10 This invention relates to new and useful improvements in hat fasteners and more particularly to a fastener which is carried by the hat so that the same may be readily secured to the head of the wearer and is the same subject matter that was embodied in a formally allowed, forfeited, and abandoned application which was filed by me on December 7, 1912, allowed May 22, 1913, and identified by Serial No. 735,502, the object of 15 the invention being to provide a hat fastener which will replace the well known form of hat pin and which can be readily manipulated to secure the hat to the head of the wearer.

20 Another object of the invention is to provide a hat fastener which will possess advantages in points of efficiency and durability, is inexpensive to manufacture and at the same time is simple in construction and operation.

25 With the above and other objects in view, the invention consists in the novel features of construction and the combination and arrangement of parts hereinafter more fully described, pointed out in the claims and 30 shown in the accompanying drawings, in which—

Figure 1 is a top plan view showing the device in its open position.

Fig. 2 is a similar view showing the same 40 in a closed position.

Fig. 3 is an enlarged elevation illustrating the detachable end of one of the sections, and

Fig. 4 is an end elevation showing the device 45 in its operative position in full lines and in an inoperative position in dotted lines.

Referring more particularly to the drawings, 1 indicates the body member of my improved hat fastener which comprises two 50 semi-elliptical sections 2 and 3, each section being formed of a suitable length of wire which may be of any weight or size. Each section is provided at one end with a pin portion 4 which is bent at substantially right angles to the body portion and having the 55

screw threads 5 formed upon the outer end thereof, said pin portions being adapted to project through the side of the crown of the hat. A head member 6 is provided having an internally threaded bore 7 formed integral therewith and adapted to be threaded upon the outer end of the pin portion 4 to securely fasten each section to the crown of the hat.

60 The ends of the sections 2 and 3 opposite the pin portion 4 are provided with the hook members 8 which are adapted to engage over the pin portions 4 adjacent the inner end thereof and be disposed upon the inner side of the crown of the hat so that each section will be pivotally mounted within the crown of the hat. It will be understood that the hook member formed upon the end of one of said sections will be engaged over the pin portion of the other section.

65 The length of wire of which each section is formed is bent upon itself at various intervals to form a series of spaced inwardly projecting and downwardly curved hook members 9 which, when the sections are disposed in the position shown in Fig. 4, the hook members will engage with the hair of the wearer. In the operation of my improved hat fastener, it will be understood 70 that the device is previously applied to the hat, the head member 6 being securely fastened upon the outer ends of the pin portions 4. When the wearer places the hat upon the head, it is simply necessary to turn the head members 6 and turn the sections 2 and 3 downwardly engaging the hook members 9 with the hair which will prevent the 75 removal of the hat until the sections have been turned upwardly to their inoperative position as shown in Fig. 4. In removing the hat, it is only necessary to turn the head members 6 until the hooks 9 have been disengaged from the hair.

80 From the above it will be apparent that I have provided a simple and durable hat fastener which replaces the old form of hat pin whereby the points thereof will be entirely eliminated. It will also be seen that the device is extremely simple in its construction, easily applied and can be manufactured at an extremely low cost. While I have shown for the purpose of illustration, the head members 6 threaded upon the outer ends of the pin portions 4, it will be understood 85 that these head members may be ap- 90 95 100 105 110

plied thereto in any suitable manner. It will also be apparent that the device as a whole may be made of any suitable material desired.

5 While I have shown and described the preferred form of my invention, it will be obvious that various changes in the details of construction and in the proportions may be resorted to for successfully carrying my 10 invention into practice without sacrificing any of the novel features or departing from the scope of the appended claims.

What I claim is:

1. In a device of the character described, 15 the combination of two semi-elliptical sections, each section being provided upon one end with a pin portion adapted to be disposed through the crown of the hat, head members engaged upon the outer ends of the 20 pin portions, the other ends of said sections being provided with a hook member to engage over the pin portions and spaced hook members carried by the body of the sections and adapted to engage the hair of the wearer 25 to securely retain the hat in position.

2. In a device of the character described, 30 the combination of two semi-elliptical sections, hair engaging means carried by each of said sections, each section having a pin portion formed at one end and a hook member formed at the other end to engage over the pin portions to pivotally connect said sections.

3. In a device of the character described, 35 the combination of two semi-elliptical sections, pin portions formed upon one end of said sections, hook members formed upon

the other ends of said sections and adapted to engage the pin portions to pivotally connect said sections, and spaced hook members 40 carried by the body of the sections and adapted to engage the hair of the wearer.

4. A device of the character described 45 consisting of two arcuate strands having their adjacent ends pivotally connected, the intermediate portions of the strands being bent upon themselves to form series of spaced hook members.

5. A device of the character described 50 consisting of two arcuate strands having their adjacent ends pivotally connected, the intermediate portions of the strands being bent upon themselves to form series of spaced hook members, each of said strands 55 having an end portion extended to afford a pin, the pin of one strand being remote from the pin of the second strand.

6. A device of the character described 60 consisting of two arcuate strands having their adjacent ends pivotally connected, the intermediate portions of the strands being bent upon themselves to form series of spaced hook members, each of said strands 65 having an end portion extended to afford a pin, the pin of one strand being remote from the pin of the second strand, and detachable head members coacting with said pins.

In testimony whereof I hereunto affix my signature in the presence of two witnesses.

CHRISTINA SWANSON.
